[57] CLAIM

The ornamental design for a speech processor for use with a cochlear implant, as shown and described.

DESCRIPTION

FIG. 1 is a perspective view of a speech processor for use

with a cochlear implant with the transmitter removed, showing our new design;

FIG. 2 is a perspective view thereof with the transmitter attached, in use condition; the broken line showing of an ear being for illustrative purposes only and forming no part of the claimed design;

FIG. 3 is a side elevational view thereof;

FIG. 4 is a side elevational view thereof, opposite that shown in FIG. 3, with the transmitter removed;

FIG. 5 is a top plan view thereof;

FIG. 6 is a bottom plan view thereof;

FIG. 7 is an end elevational view thereof;

FIG. 8 is an end elevational view thereof, opposite that shown in FIG. 7;

FIG. 9 is a top plan view thereof in disassembled condition with the battery compartment removed;

FIG. 10 is a side elevational view thereof, with the battery compartment removed;

FIG. 11 is a side elevational view thereof, with the battery compartment removed and a cable attaching the battery compartment to the speech processor; and,

FIG. 12 is a side elevational view thereof, with battery cover removed.
